Attorney

UNITED STATES PATENT OFFICE.

FRANK S. LASH, OF SAGINAW, MICHIGAN, ASSIGNOR TO JACKSON & CHURCH CO., OF SAGINAW, MICHIGAN, A CORPORATION OF MICHIGAN.

JOINTER.

Application filed November 23, 1925. Serial No. 70,850.

This invention relates to jointers and consists of an improvement on an old machine whereby certain disadvantages in operation are overcome, such as jerky motion of the feed mechanism and gouging the fingers into the work, and certain new and better results are obtained, such as smoothness of operation and longer working life of the feeding fingers.

10 The type of old machine to which my improvement is applicable is that of the jointer shown in Herzog Patent No. 919,351. In this machine there is an automatic mechanism for feeding the work to the revolving 15 cutters, whereby danger incident to hand feeding is avoided. In that machine there is also provided mechanism which feeds the work with a slight pressure thereon so as not to bind or spring the board from its natural 20 shape, in order to produce a perfectly straight plain surface.

As is well known in the art, the feed mechanism of the Herzog machine is mounted upon a frame and is adjustable therewith toward and from the bed of the jointer to accommodate different thicknesses of work. This feed mechanism consists of an endless chain that engages sprockets on cross shafts at opposite ends of the frame.

30 The carrier is formed with parallel chain members engaging the sprockets and a series of cross bars connecting the chain and spanning the bed of the machine from side to side, to these cross bars the work feeding 35 devices are secured. These feeding devices consist of fingers or sharpened pins slidably mounted in the cross bar and yieldingly pressed downward by springs. The tension of these springs is only sufficient to engage 40 the points of the fingers with the upper surface of the board without springing the board from its natural shape, and the large number of fingers that are simultaneously engaged with the board exert sufficient driving force to feed the work across the bed of the jointer.

A machine of the kind to which my improvement is adapted to be applied may, as in the foregoing patent, be described as a jointer having an endless work carrier comprising a pair of parallel sprocket-supported chains, one at each side of the machine bed, a series of cross bars connecting said chains, and a plurality of fingers arranged longitudinally on each cross bar, and projecting

into engagement with the work, each of said fingers comprising a vertical member projecting on both sides of the cross bar, a spring encircling said vertical member and adapted to limit the outward movement of the vertical member.

The particular idea, which is the essence of my present invention, relates to a means by which the fingers of successive flights are positioned substantially at right angles to the face of the work before the fingers are brought into contact with the work.

In the accompanying drawings I have illustrated those features of the invention covered by the claims. Fig. 1 is a side view broken away in part, showing an end of the work carrier with my improvement applied thereto.

Fig. 2 is a side view, showing the connection of my improvement with a jointer of the old Herzog type.

As will be readily understood by those familiar with the machine, or upon reference to the patent above referred to, the work carrier includes a frame 1 having mounted thereon at each side of the bed an endless chain 2 carried by driving sprockets 3 and driven sprockets 4, the direction of travel of the chain being as shown by the arrow in Fig. 2. The lower or working run of the chain runs upon a horizontal track 5 and is held down by an upper track-member or guide rail 6.

As the chain is drawn forward by the action of driving sprockets 3, it is obvious that the slack part of the chain runs off from sprockets 4 and comes around upon the horizontal track 5 bringing the sharpened ends of fingers 7 into engagement with the work 8 at a point below and slightly in advance of the idle sprockets 4.

It has frequently occurred that when there is sufficient slack in chain 2 after running off the sprocket 4 it would sag down beneath sprocket 4 so as to let the fingers 7 come into contact with the surface of the board while the fingers had a pronounced rearwardly raked position, as indicated in Fig. 1.

The result of letting the finger points contact with the board with the fingers in an oblique position was to make the working points of the fingers to gouge into the board as soon as the chain was forced into its nor-

mal position with the fingers 7 upright, upon entering the guiding groove formed by the track members 5 and 6.

The strain thus produced resulted in a 5 jerky and uneven movement of the feed and inferior planing, and it is to overcome those objections and to provide perfectly smooth operation, regardless of the amount of slack in the chain beneath sprocket 4 that my 10 present improvement is adapted.

In order to position the successive chain members 2 so that their fingers 7 will be approximately perpendicular to the face of the board 8 before the fingers can contact 15 with the board, even though the chain be slack as it runs off sprocket 4, I provide on the track member 5, beneath the sprocket 4 and in advance of the track member 6, as shown in Fig. 1, a guide block 9 having a 20 flat forwardly and downwardly inclined upper surface 10. The blocks are wedge shaped pieces of metal having flat upper surfaces to form runways for supporting the links of the chains between the time of their 25 leaving the chain sprockets 4 and their contacting with the horizontal track 5. Each block is secured by countersunk bolts or otherwise to the horizontal track 5. The slack of the chain allows each of its finger-carrying links to seat flat upon this inclined surface 10 before the sharpened ends of fingers 7 can come in contact with the work 8. This seating of the finger-carrying links 30 flat upon incline 10 before the fingers can come into operation results in presenting the fingers to the work while they are nearly at right angles to the plane of the work instead of at a dragging angle of inclination. The chain link rests upon the inclined face 35

10 of block 9, and as the chain travels forward the link slides down the incline and its finger 7 is gradually lowered until its end contacts with the board, but that contact will always be substantially at right angles with the board. Binding or gouging heretofore 45 caused by the finger coming into working contact while still oblique to the board is avoided, and proper smoothness and uniformity of feeding is assured.

By the means above described I have overcome one of the principal difficulties of operation that have been encountered in practice in jointers of this kind, and although the improved construction is simple it has for the first time overcome difficulties in the 55 operation of these machines that have long been known to exist, but for which no adequate remedy has heretofore been devised.

Having thus described my invention, what I claim and desire to secure by Letters 60 Patent is:

In a jointer of the class described including a traveling carrier comprising chain supported flights having spring-pressed work-engaging fingers, sprockets supporting 65 said chain, a guide track beneath the lower run of said chain and a guide member secured to said track beneath a sprocket, the upper face of said guide member forwardly and downwardly inclined to provide a support for the slack part of said chain beneath the sprocket, whereby the fingers of successive flights are positioned substantially at 70 right angles to the face of the work before said fingers are brought into contact with 75 the work, for the purposes set forth.

In testimony whereof, I affix my signature.

FRANK S. LASH.
